UNITED STATES PATENT OFFICE.

JOHN B. EGER, OF CHICAGO, ILLINOIS.

AUTOMOBILE SIGNAL.

1,414,346.

Specification of Letters Patent.

Patented May 2, 1922.

Application filed June 20, 1921. Serial No. 478,976.

To all whom it may concern:

Be it known that I, JOHN B. EGER, a citizen of the United States, and a resident of the city of Chicago, county of Cook, and State of Illinois, have invented certain new and useful Improvements in Automobile Signals, of which the following is a specification.

This invention relates to automobile signals, and has for its object the provision of a device which will indicate intended movements of a vehicle by the display of signals at the rear end thereof, and which is adapted to be illuminated when necessary to render the signals conspicuous, and at the same time serve as the usual tail light ordinarily required on such vehicles.

Other objects will appear hereinafter.

The invention consists in the combinations and arrangements of parts hereinafter described and claimed.

The invention will be best understood by reference to the accompanying drawings forming a part of this specification, and in which,

Fig. 1 is a fragmentary view of an automobile showing the signaling device applied to the rear end thereof;

Fig. 2 is a sectional view of the casing and drum on the line 2—2, Fig. 3;

Fig. 3 is a longitudinal section on the line 3—3, Fig. 1;

Fig. 4 is a detail view on the line 4—4, Fig. 3; and

Fig. 5 is a front view of the signaling device showing same in operative position.

Signals of this type as heretofore used have been complicated, unreliable in operation and of expensive construction. My device as illustrated in the drawings is preferably constructed of sheet metal and is very simple and positive in operation and can be manufactured very cheaply.

As shown in the drawings, the signal comprises a casing 1 which is preferably provided with an opening 2, which opening is adapted to be closed by means of a hinged door 3 which is provided with a sheet of transparent or translucent material, preferably celluloid, so as to permit a clear view of the interior of the casing. A suitable spring hook as shown at 4 is preferably provided for retaining the door in closed position.

Rigidly mounted in the casing 1 is a shaft

5, and secured to said shaft at one end thereof is a bearing member 6, which is provided with a slot 7 through which passes an electrical wire 8 leading to a bulb 9 mounted on the shaft 5 by means of a bracket 10.

Revolubly mounted on the shaft 5 and bearing member 6 is a sheet metal drum 11. This drum bears suitable indicia, preferably punched in its periphery, and adapted to be successively displayed before the opening 2 in the casing 1 when the drum is revolved. This indicia consists of suitable words such as "Left" "Right" "Stop," etc., each of said words being displayed before the opening 2 when the drum 11 is revolved. To permit access to the interior of the drum to repair or adjust the device I preferably provide the drum 11 with a rectangular opening 12 which opening is adapted to be closed by a plate 13, which may be provided with small spring clips 14 adapted to engage beneath the edges of the opening 12 as shown. The plate 13 also is provided with an opening 15 adapted to receive a suitable transparent or translucent closure 16 preferably red in color. This closure when illuminated by the bulb 9 serves as a tail light, the signal being normally retained in such position that the colored lens remains before the opening 2 in the casing 1 at all times except when the signal is operated to position the desired indicia before said opening.

The drum 11 preferably has disposed about its inner periphery some light colored material 17, preferably white muslin, which provides a suitable background for the indicia punched in the periphery of the drum 11. The muslin 17 may be secured to the interior of the drum 11 in any suitable manner, as by glue or the like, but I preferably retain same in position by means of a sheet of resilient material, celluloid being preferred, which is indicated at 18 in the drawings. The drum 11 may have its exterior painted a dark color, and the white muslin 17 viewed through the punched out portions of the drum will provide a contrast which will render the indicia on the drum conspicuous and plainly visible at some distance during the daylight hours, and in the evening when the bulb 9 is used, light rays therefrom will pass through the muslin and the punched out letters and render same clearly visible when the signal is operated. When in inoperative position, the light rays will

pass through the colored lens 16 and provide a tail light for the vehicle.

In order to revolve the drum 11 so as to present the desired signal before the opening 2 in the casing 1, a hub or reel 19 is mounted at one side of the drum 11 and is adapted to revolve therewith. Secured to the shaft 5 adjacent the reel 19 is one end of a coiled spring 20, the other end of such spring being secured to the reel 19 as shown. The spring 20 normally retains the drum 11 in inoperative position, in which position the colored lens is retained before the opening 2 in the casing 1.

15 Wound on the reel and having one end attached thereto is a cable 21 which when unwound against the tension of the spring 20 will revolve the drum 11 so as to display the various signals thereon successively before the opening 2 in the casing 1. The other end of the cable 21 is preferably attached to a suitable form of operating means for selectively displaying the signals before the opening in the casing 1.

25 While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

35 Having described my invention, what I claim as new and desire to secure by Letters Patent is:

1. In a signal of the character described comprising a casing having an opening therein; a drum mounted in said casing; indicia punched in the periphery of said drum; an opening in said drum; a plate for said opening; spring clips on said plate adapted to secure same in said opening; a lens mounted in said plate, said plate being normally retained before the opening in said casing; and means for revolving said lens and said indicia past the opening in said casing, substantially as described.

50 2. In a signal of the character described comprising a casing; a shaft mounted in said casing; a bearing member on said shaft; a drum revolvably mounted on said bearing member and said shaft; an elec-

tric bulb mounted on said shaft; and a slot 55 in said bearing permitting the passage of a connection to said bulb, substantially as described.

3. In a signal of the character described comprising a casing; a drum having indicia punched in its periphery; flexible translucent material disposed about the interior of said drum to provide a background for said indicia; and a sheet of resilient material to retain said translucent material in position in said drum, substantially as described.

4. In a signal of the character described comprising a casing; a drum having indicia punched in its periphery; an opening in the periphery of said drum; a sheet of resilient translucent material disposed about the interior of said drum to provide a background for said indicia, said sheet being held thereagainst by reason of its resiliency, and means for holding the ends of said sheet to prevent movement thereof over said opening; substantially as described.

5. In a signal of the character described comprising a casing; a drum having indicia thereon revolvably mounted in said casing; an opening in said drum to permit access to the interior thereof; a plate for closing said opening; and spring clips mounted on said plate and adapted to be inserted in said opening to hold said plate therein, substantially as described.

6. In a signal of the character described comprising a casing; a drum having indicia punched in its periphery mounted in said casing; an opening in said drum; a plate for closing said opening, said plate being provided with inwardly projecting spring clips; and a sheet of resilient translucent material disposed about the interior of said drum to provide a background for said drum, the ends of said sheet engaging said inwardly projecting clips and being held in position thereby, substantially as described.

In testimony whereof I have signed my name to this specification in the presence of two subscribing witnesses.

JOHN B. EGER
